TUBE END FORMING MACHINE

Charles Eisler, South Orange, N. J.

Application January 26, 1945, Serial No. 574,800

4 Claims. (Cl. 49—7)

1

This invention relates to tube forming machines. An object of this invention is to provide a forming tool for incorporation in a tube forming machine, said forming tool, in operation, forming the ends of tubes in a rapid, efficient and novel manner. It has been the practice in this art to form only one end of the tube at one run through the machine, and to then reverse the tube and run it through the machine a second time to form the other end. This procedure was costly and time consuming.

A further object of this invention is to provide a machine incorporating forming tool units which will permit both ends to be formed on tubes at one run through the machine.

A further object of the invention is to provide a machine which is of such structure as to be adjustable for use in connection with tubes of different lengths and diameters.

In the drawings:

Fig. 1 is a top plan view of a tube end forming machine embodying my invention,

Fig. 2 is an enlarged fragmentary, partly sectional elevational view of one of the forming tools of said machine and associated parts shown in the operative position, the inoperative position being indicated in dotted lines,

Fig. 3 is an elevational view of the forming end of said tool, taken on line 3—3 of Fig. 2,

Fig. 4 is an enlarged longitudinal, fragmentary, partly sectional view of the forming tool in the inoperative position,

Fig. 5 is a similar view thereof in its initially operative position,

Fig. 6 is a fragmentary top plan view of the adjustable forming tool and associated parts incorporated in the machine of Fig. 1,

Fig. 7 is a sectional elevational view of the main support for said tool showing one form of height adjusting means taken on line 7—7 of Fig. 6,

Fig. 8 is a fragmentary, sectional elevational view taken on line 8—8 of Fig. 6, and

Fig. 9 is a top plan view of a tube shown at A before and at B after the same has been passed through the machine of my invention and subjected to end forming operations therein.

My invention is especially adapted for use in connection with tubes such as the fluorescent tubes shown in Fig. 9; the invention may be used in connection with other objects which may be adapted to have one or both ends thereof formed in the machine herein disclosed.

In the drawings, wherein parts of similar physical features and functions are correspondingly numbered, there is shown a machine embodying my invention, said machine including the table 10 having the hopper 11 to initially receive the tubes A and from which the tubes pass on to the conventional tube-rotating and dwelling device by any suitable forwarding mechanism, exempli-

2

fied in the drawings by the notched rails 12 which pick up, forward and deposit the glass blanks from one dwelling station to the next, and which are actuated to that end by any suitable means, as will be apparent to those skilled in this art. The tube rotating and dwelling device includes the roller discs 13 at the adjustable side 119 of the machine and the oppositely located roller discs 14 at the fixed side 120 thereof, the roller discs being mounted on the revolving shafts 15, 16, 17, 18 and 19 which are driven by the usual chain and belt transmissions such as are well-known in the glass forming art. The shafts are actuated from main drive shaft 20, the shaft 20, chain drive 21a and belt 22 being driven by means of worm drive 21 of the motor 23. The description of chain-driven parts herein is intended merely to illustrate one of many possible forms of power means, for convenience in illustrating the application of the invention to the machine shown in the drawings. The disc shafts are journaled at opposite ends in the fixed supports 24 and 25 and are slidably journaled intermediate their ends in the movable support 26. The support 26 is movable relative to support 25 by any suitable means as by the hand-wheel 27 on the screw shaft 28 which is journaled at 29 in the fixed support 24 and has screw engagement with the movable support 26 at 30.

As indicated by dotted lines, the ends of the tubes overhang the disc rollers at either side and are held in alignment by the aligning rail 31 adjustably mounted relative to support 25 in bearings 31', and by the fixed aligning rail 32. The ends of the tubes are heated to the required degree of plasticity by the fixed burners 33 at the fixed side 120 of the machine and by the burners 34 at the adjustable side 119, the latter burners being mounted in the manifold 35 which is movably mounted relative to support 25. The burners are supplied with a mixture of gas, air and oxygen or other heating medium by ducts 36 and 37.

The forming tool illustrated in Fig. 2 has the plunger shaft 38 provided at one end with the forming die 39 which has the circumferential flange 40. Plunger shaft 38 is nonrotatably and slidably arranged in bearing 41 of the main tool support 42. It is actuated to insert the die 39 into the end of the tube A by the lever 43 bearing on lug 44 which is slidably keyed on the plunger shaft, the spring 45 being interposed between the lug 44 and a collar 46 secured on the plunger shaft by the set screw 47, for the purpose of easing the insertion and retraction of the forming die 39.

The plunger shaft is retracted after the forming operation responsive to spring 48 interposed between collar 49 and extension support 50 (Fig. 2). Its forward travel is limited on abutment of 60 a stop means, such as the adjustable pins 51 in

collar 51a fixed to shaft 38, with the main tool support. The plunger shaft has the reduced end portion 52 on which sleeve 53 is rotatably mounted, said sleeve having keyed thereto the gear 53 meshing with driving gear 55 on drive shaft 56. On sleeve 53 is fixed bracket 57 having the two slots 58 in which are slidably retained the roller carrying blocks 59, at one end of which the forming rollers 60 are rotatably mounted. Said blocks (and the forming rollers 60) are normally urged radially to the outer ends of the slots 58 of bracket 57 by springs 62 or the like. At their other ends the roller blocks 59 are provided with the friction rollers 61. In order to bring the forming rollers toward the forming die 39 and into their operative position, the blocks 59 are moved toward the inner ends of the slots 58 of bracket 57 against the tension of springs 62 by engagement of the conical inner face 63 of the cone 64 with the friction rollers 61. To this end the cone 64, which is preferably screwed on the sleeve 53a and locked in place by lock nut 65 is moved forward (that is in toward glass blank A) by clutch fork 66 mounted on clutch shaft 67. The clutch shaft 67 has slideable bearing in the main tool support 42 (Fig. 6) and is moved forward by lever 68 engaging lug 69 which is slidably keyed on the clutch shaft, the spring 70 being interposed between lug 69 and the fixed collar 71—an arrangement corresponding to that on plunger shaft. The cone 64 is retracted by the clutch shaft responsive to the spring 72 (which was compressed during the forward stroke) spring 72 being interposed between the extension support 59 and collar 73 fixed to shaft 67.

As during the forming operation, the rotation of the glass tube would normally be retarded and even stopped by adhesion of the end of tube A to the non-rotating die 39. The glass tube is kept turning by the overhead asbestos roller 74, which is raised after the forming operation. The asbestos roller is journaled in bracket 75 which is maintained in its vertical position by the parallel levers 76 pivoted at opposite ends in the bracket 75 as at 77 and in the main tool support at 78. The asbestos roller 74 is raised and lowered by member 79 pivoted at 79' to the bell crank 80, the latter being pivoted at 80' to the lug 81 of the main tool support and having pivotal connection 82 with collar 83 fixed to the plunger shaft.

When the plunger shaft moves back, and thereby retracts the entire forming device, the bell crank will be turned (as shown dotted in Fig. 2 and by the arrow in Fig. 4) and the parallel levers 76 and asbestos roller 74 will thereby be raised.

The asbestos roller is driven by a chain drive which includes the drive sprocket 84 on the drive shaft 56, the driven sprocket 85 on shaft 86 journaled in the main tool support and the universal jointed transmission shaft 87, the latter comprising slidably coupled portions terminations in universal joints connecting the shaft for the asbestos roller 74 with the shaft of sprocket 85.

Overhead heating of the glass tube during forming is effected by the overhead burner 88 fed through gas duct 89 which is carried in brackets 90 on the parallel levers 76. The burner 88 thus moves with the asbestos roller and is ineffective as long as the roller is up.

Fig. 4 shows the relative position of the forming rollers 60 and die 39 during the inactive period, the arrows indicating the directions in which the parts have moved to their inactive position. The forming rollers have moved radially outward away from die 39 and the cone 64 has been re-

tracted with respect to the forming rollers. The bell crank 80, shown schematically, has elevated the asbestos roller 74 clear of the tube A.

Fig. 5 shows the forming tool at the commencement of the operative period. The plunger shaft 38 has been advanced to carry the die 39 inside the end of the glass tube A, turning the bell crank 80 to lower the asbestos roller 74. The forming rollers 60 remain in their outermost position relative to the die 39 until the clutch shaft 67 is actuated to advance the cone 64 into engagement with rollers 61.

In Fig. 2 the tool is shown in operation. The clutch shaft 67 has advanced the cone 64 toward bracket 57 so that the forming rollers 60 move radially inward toward die 39 and down on the neck of the tube.

In the construction described, the cone 64 is rotatably arranged on the sleeve 53 so that the cone may run freely, to "creep" around the sleeve, and consequently the wear caused by the friction rollers 61 will be distributed all over the inner cone surface 63, avoiding scoring which would occur if the cone did not rotate; scoring would adversely affect the exact spacing of the forming rollers 60.

The levers 68 and 69 are provided with cam surfaces to be engaged by cams 93 and 94, 93', 94' respectively (Fig. 8) on cam shaft 95 for the adjustable tool 117 and cam shaft 96 for the fixed tool 118, both cam shafts being driven from main drive shaft 26 by bevel gears 97 and 98.

The machine is designed to handle tubes in a wide range of lengths, for example from 15" to 60" in length; the main tool support 42 is shifted inward and outward in gibbs 99 retaining base plate 100 of the support.

The adjustable tool 117 is driven as follows (Figs. 6 and 8):

Shafts 16 and 17 are extended outward and have bearing in the separate supports 101 and 102 respectively. On shaft 16 is mounted sprocket 103 (Fig. 8) which (by chain 104 over sprocket 105) drives countershaft 106 in support 107. On countershaft 106 is mounted sprocket 108 which by chain 109 drives sprocket 110 on tool drive shaft 56.

For moving tools inward plunger shaft 38, drive shaft 56 and clutch shaft 67 are extended outward through supports 50 and 111 on extension plate 112.

Shafts 38 and 67 are splined in their supports by spline grooves 113 and 114 respectively.

Fixed tool 118 is driven the same way but its shafts 18 and 19 are not extended.

All shaft supports can be adjusted vertically for different diameter tubing by adjusting screws 115 and lock nuts 116 or similar means.

In Fig. 1 the parts of the machine at the side 119 thereof, including the tool forming unit 117, are adjustable relative to the complementary or corresponding parts at the fixed side 120 of the machine, so as to accommodate the machine for the reception of tubes of various lengths.

The term "adjustable" applied to tool 117 is intended to indicate that the tool 117 may be moved laterally relative to the fixed support 24 to correspond with the particular length of the tube or other objects to be formed in the machine. The manifold 35 may be movably mounted in any manner in which parts may be moved. The means to movably mount the same are not specifically claimed and may be any means suitable to the purpose. It is possible to adjustably mount the tool 117 while maintaining its association with the actuating and driving means

for its parts, by virtue of the fact that the parts, such as 46 and 51a, the sprocket 84 for the chain, the bracket 57, etc., (see Fig. 2), are mounted by set screws. The member 26 supports the disc shafts intermediate the fixed supports 24 and 25. It would be desirable to so position the support 26 that it would be relatively adjacent the aligning rail 31 and the position of the latter would depend upon the particular width of tubes being run through the machine.

The machine of my invention is adapted to form both ends of tubes by the forming tools 117 and 118 at one run through the machine and to accommodate tubes of various lengths, and diameters.

Having thus described my invention what I claim as new and desire to secure by Letters Patent, is:

1. In a tool for forming the end of a tube, a bearing, a plunger shaft slidably arranged in said bearing, a forming die fixed to one end of said shaft, a flange on said forming die, means on said shaft to reciprocate the same in said bearing to advance and retract the forming die relative to the end of the tube, a bracket mounted on said shaft, roller members slidably mounted on said bracket in alignment with said forming die for cooperation therewith to form the end of the tube on said die and against said flange, means on said bracket engaging the rollers to normally urge the latter away from the forming die, a cone mounted on said shaft and adapted, on engagement with said roller members, to move the latter toward the forming die for cooperation therewith to form the end of the tube, and means engaging said cone to move the same into and out of engagement with said roller members.

2. In a tool for forming the end of a tube, a bearing, a plunger shaft slidably arranged in said bearing, a forming die fixed to one end of said shaft, a flange on said forming die, means on said shaft to reciprocate the same in said bearing to advance and retract the forming die relative to the end of the tube, a bracket mounted on said shaft, roller members slidably mounted on said bracket in alignment with said forming die for cooperation therewith to form the end of the tube on said die and against said flange, means on said bracket engaging the roller members to normally urge the latter away from the forming die, a cone mounted on said shaft and adapted, on engagement with said roller members, to move the latter toward the forming die for cooperation therewith to form the end of the tube, and means engaging said cone and shaft to move the same into and out of engagement with said roller members, to advance the forming die toward the tube and move the roller members toward the forming die, in unison.

3. In a tool for forming the end of a tube, a bearing, a plunger shaft slidably arranged in said bearing, a forming die fixed to one end of said shaft, a flange on said forming die, means on said shaft to reciprocate the same in said bearing to advance and retract the forming die relative to the end of the tube, a bracket mounted on said shaft, roller members slidably mounted on said bracket in alignment with said forming die for cooperation therewith to form the end of the tube on said die and against said flange, means on said bracket engaging the rollers to normally urge the latter away from the forming

die, a cone mounted on said shaft and adapted, on engagement with said roller members, to move the latter toward the forming die for cooperation therewith to form the end of the tube, and means engaging said cone to move the same into and out of engagement with said roller members, a bracket pivoted to said bearing, a tube heating member carried by the bracket and normally disposed sufficiently adjacent the forming die to heat the tube to be formed thereon, means connecting the plunger shaft and bracket for movement thereof in unison, and means to actuate said connecting means, whereby, when the plunger shaft is moved toward the tube end, the bracket will pivot to carry the tube heating member sufficiently adjacent the die to heat the end of the tube being formed, and, when the plunger shaft is retracted away from the tube end, the bracket will be pivoted to carry the tube heating member away from the tube end.

4. In a tool for forming the end of a tube, a bearing, a plunger shaft slidably arranged in said bearing, a forming die fixed to one end of said shaft, a flange on said forming die, means on said shaft to reciprocate the same in said bearing to advance and retract the forming die relative to the end of the tube, a bracket mounted on said shaft, roller members slidably mounted on said bracket in alignment with said forming die for cooperation therewith to form the end of the tube, on said die and against said flange, means on said bracket engaging the rollers to normally urge the latter away from the forming die, a cone mounted on said shaft and adapted, on engagement with said roller members, to move the latter toward the forming die for cooperation therewith to form the end of the tube, and means engaging said cone to move the same into and out of engagement with said roller members, a bracket pivoted to said bearing, a tube heating member carried by the bracket and normally disposed sufficiently adjacent the forming die to heat the tube to be formed thereon, means connecting the plunger shaft and bracket for movement thereof in unison, and means to actuate said connecting means, whereby, when the plunger shaft is moved toward the tube end, the bracket will pivot to carry the tube heating member sufficiently adjacent the die to heat the end of the tube being formed, and, when the plunger shaft is retracted away from the tube end, the bracket will be pivoted to carry the tube heating member away from the tube end and means carried by the bracket to engage the tube to rotate the latter when the bracket is pivoted to the position in which the tube heating member heats the end of the tube.
